UNITED STATES PATENT OFFICE.

OWEN H. HUDGEN, OF LOS ANGELES, CALIFORNIA.

SANITARY SHIELD FOR TELEPHONES.

No. 910,383.

Specification of Letters Patent.

Patented Jan. 19, 1909.

Application filed June 10, 1907. Serial No. 378,119.

To all whom it may concern:

Be it known that I, OWEN H. HUDGEN, a citizen of the United States, residing at Los Angeles, in the county of Los Angeles and State of California, have invented new and useful Improvements in Sanitary Shields for Telephones, of which the following is a specification.

My invention relates to a shield for telephone transmitter mouthpieces, and an object thereof is to provide a sanitary shield which may be readily put on the mouthpiece and quickly removed therefrom and sterilized. I accomplish this object by means of 15 the device described herein and illustrated in the accompanying drawings, in which:—

Figure 1—is a plan of my improved shield. Fig. 2—is a central cross section of the same. Fig. 3—is a view of a telephone transmitter 20 mouthpiece equipped with my shield.

Referring to the drawings, 5 designates a disk of elastic material, preferably rubber, having a beaded edge 6 also preferably of rubber. The body portion of the disk is 25 made very thin so that it will not impede the passage of sound waves to the transmitter when on the mouthpiece in the position shown in Fig. 3. The bead is heavier than the body portion and its diameter is considerably less than the diameter of the mouthpiece so that the whole shield must be stretched in order to put it on the mouthpiece 30. When in this position as, illustrated in Fig. 3, the elasticity of the beaded edge

holds the shield from slipping off and the disk portion is stretched tightly over the mouthpiece.

It will be observed that I have produced a shield which is at once convenient and extremely sanitary as it may be easily removed 40 from the mouthpiece and thoroughly sterilized before replacing. Being of thin elastic, material it does not impede the passage of sound waves to the transmitter diaphragm and so does not impair the efficiency of the 45 telephone.

Having described my invention what I claim as new and desire to secure by Letters Patent is:—

A telephone transmitter shield, comprising a circular diaphragm of relatively thin elastic material and of a smaller diameter than the telephone mouth piece, said diaphragm having formed integrally therewith on its periphery an annular rib 55 of relatively heavy elastic material, said rib being substantially circular in cross-section and projecting equally beyond the plane of each face of the diaphragm, whereby either side may be utilized as an outer face. 60

In witness that I claim the foregoing I have hereunto subscribed my name this 1st day of June, 1907.

OWEN H. HUDGEN.
